ALEXANDER WADDELL, OF DUNFERMLINE, SCOTLAND.

MANUFACTURE OF COAL-GAS.

1,249,864.

Specification of Letters Patent. Patented Dec. 11, 1917.

Application filed February 29, 1916. Serial No. 81,108.

To all whom it may concern:

Be it known that I, ALEXANDER WADDELL, a subject of the King of the United Kingdom of Great Britain and Ireland, and residing at Dunfermline, Fifeshire, Scotland, have invented a certain new and useful Improvement in the Manufacture of Coal-Gas, of which the following is a specification.

This invention relates to a process of and apparatus for the manufacture of coal gas.

The process, as practised may consist of either of the following combinations of steps:—

(1) Passing the coal downward through a retort, subjecting the coal to carbonization in the retort while so regulating the heating action that the temperature at which carbonization is effected is progressively increased from the upper end of the retort downward, repeatedly changing the direction while contracting the cross-sectional area of the descending mass toward the lower end of the retort, the changing of direction being initiated before the hottest zone is reached, discharging the coke at the lower end of the retort, and withdrawing the gas at the upper end of the retort and bringing the gas into contact with the entering coal, whereby tar may be condensed and returned to the retort with the descending coal for carbonization therewith. Or,

(2) Passing coal downward through a retort, subjecting the coal to carbonization in the retort while so regulating the heating action that the temperature at which carbonization is effected is progressively increased from the upper end of the retort downward, repeatedly changing the direction and at the same time contracting the cross-sectional area of the descending mass toward the lower end of the retort, the changing of direction being initiated before the hottest zone is reached and withdrawing gas freed from tar as far as may be at a point toward the lower end of the retort.

The construction of retort employed consists of a vertical upper section and an inclined lower section comprising sub-sections inclined in opposite directions, both of such sub-sections being heated.

The invention thus provides a construction wherein completion of the carbonization initiated in the vertical section of the retort is effected by reason of the selection of the inclination of the lower section so as to effect sufficient change of direction of the material passing through the retort, and by reason of the large area of the inclined surface exposed to heating action. 55

It is understood, of course, that consequent on each change of direction of the descending mass the uncarbonized or partly carbonized core is brought in part at least to the exterior of the charge in the retort so that more complete or more rapid carbonization of the charge is effected. Whether the tar which has been condensed out adheres to the coal, or runs down the comparatively cold uncarbonized core in the vertical section, it must at least come into contact with a sufficient extent of the heated sloping surface to carbonize it, avoiding the running out of tar from the lower mouth piece. 60 65 70

A subordinate feature of the invention consists in an improved construction of regenerator comprising individually removable upright tubes fitted into upper and lower tube-sheets. 75

In the accompanying drawing there is illustrated a construction embodying the invention and comprising several retorts, it being understood that the improvements are equally applicable to single retorts. 80

Figure 1 is a vertical section on the line C—C of Fig. 2. Fig. 2 comprises a vertical section on the line A—A of Fig. 1. Figs. 3 and 4 are vertical sections at right angles to each other and Fig. 5 a plan showing the improved construction of regenerator. 85

It is understood that the vertical sections 1 are heated externally by the combustion of gas supplied from a producer or producers 2. 90

The retorts proper rest on the arches 3 which also form the roofs of the producers. The arches 3 are formed with a number of 95 ports 4 through which pass the producer gases which are mixed with air in various sections of the flues and ignited to heat the retort as desired.

At the lower end of the vertical sections 1 100

is disposed a flue 7 of pentagonal form in section, through which flue heating gases are led, the sides of the flue being spaced from the walls and floors of the retort so as 5 to form at the lower end of each vertical retort section a section comprising oppositely inclined sub-sections 6 and 6' heated all around by combustion of producer gas as above described, the cross-sectional area of 10 the passage being contracted with the change in direction.

Normally closed openings 10 in the retort walls permit access for stirring or poking the charge.

15 Exterior to, and alongside, the producers 2 is a chamber 11 into which the hot coke is withdrawn, part of the coke pushed along a chute from 15 and 16 to the producer 2; the remainder being cooled by steam within the 20 chamber 11.

This arrangement permits of the removal of the coke in trucks traveling on a single set of rails.

Gas off-takes are shown at 12, 13 and 14. 25 The gas is taken off at 14 when it is desired to employ the process first above described, while gas is taken off at 12 when the second process is to be performed. The most usual position for the gas off-take in a vertical retort is at 13.

The charging hopper forming an extension of the upper end of each retort is or may be so dimensioned as to be capable of holding a charge of coal of a capacity sufficient to 35 effect condensation of tar.

The regenerator shown comprises vertical tubes 15 preferably of polygonal section, for example, of square or diamond section, inserted in tube sheets 16 and 17 fitted in a 40 flue 18 surrounding the retort structure and constitutes a heat exchanger for transference to the combustion-supporting air of part of the heat which would otherwise be conducted by the flue gases to the chimney.

45 In order that the tubes 15 may be readily accessible and capable of convenient insertion, replacement or renewal without interruption of the operation of the regenerator, I employ a large number of individually removable tubes of small size, and in single lengths, and therefore readily portable, which are held in the tube sheets 16 and 17 without any permanent joint, being simply inserted in orifices of the tube-sheets. A 50 cover 19 is fitted above the upper tube-sheet 16 so as to be readily removable, a sufficient free space being left for inspection removal and renewal or replacement of tubes or for the repair of the sheets constituting the interior walls or upper and lower floors of the 55 regenerator.

To avoid loss of heat by radiation, the outside walls of the regenerator may be jacketed

and the air passed through the jacket on its way to the regenerator.

The air to be heated, being practically free from matter liable to be deposited, may be passed through the tubes, the direction of flow being indicated by arrows in full lines, the flue gases being led around the exterior 70 of the tubes as indicated by dotted arrows; but the converse arrangement may be adopted.

To prevent formation of lanes the tubes are preferably disposed in staggered relationship as shown.

Columns 20 serve as supports for the tube sheets and as baffles for diverting the flow of the flue gases.

Before insertion, plastic jointing may be 80 applied to the lower end of each tube, which is then passed through a slip socket in the upper tube sheet 16 and entered in a stop socket in the lower sheet 17, the plastic jointing being pressed between the lower 85 end of the tube and the stop end of the socket, sand or other dry jointing material being then run through perforations in the bottom of the upper socket to fill up the vacant space and form a joint in the lower socket. 90

The upper joint may be formed by asbestos rope or the like covering the perforations in the bottom of the upper socket, the residual space being filled with dry jointing material.

It will be seen that the joints may be conveniently formed *in situ* and that any and every tube may be conveniently withdrawn and replaced without stopping the operation of the regenerator.

What I claim is:—

1. A process of obtaining coal gas consisting in passing a mass of coal downward through a retort, subjecting the mass to carbonization in the retort while so regulating the heating action that the temperature at which carbonization is effected is progressively increased from the upper end of the retort downward, repeatedly changing the direction of movement of the mass in process of being carbonized while contracting the cross-sectional area of the descending mass toward the end of its travel through the retort, the changing of direction being initiated before the hottest zone is reached, discharging at the lower end of the retort the coke produced, and withdrawing the gas practically free from tar.

2. A process of obtaining coal gas consisting in passing a mass of coal downward 120 through a retort, subjecting the mass to carbonization in the retort while so regulating the heating action that the temperature at which carbonization is effected is progressively increased from the upper end of the 115 retort downward, repeatedly changing the

direction of movement of the mass in process of being carbonized and at the same time contracting the cross-sectional area of the descending mass toward the lower end of 5 the retort, the changing of direction being initiated before the hottest zone is reached, and withdrawing gas at a point toward the lower end of the retort.

In testimony whereof I have signed my name to this specification in the presence of 10 two subscribing witnesses.

ALEXANDER WADDELL.
